UNITED STATES PATENT OFFICE

124,824

DESIGN FOR A RING

Louis Vogel, Chicago, Ill., assignor to J. Milhening, Inc., Chicago, Ill., a corporation of Illinois

Application November 12, 1940, Serial No. 96,461

Term of patent 7 years

To all whom it may concern:

Be it known that I, Louis Vogel, a citizen of the United States, residing at Chicago, in the county of Cook and State of Illinois, have invented a new, original and ornamental Design for a Ring, of which the following is a specification, reference being had to the accompanying drawing forming a part thereof:

In the drawing:

I claim:

The ornamental design for a ring, substantially as shown.

LOUIS VOGL,
